E. Burton Benjamin, Highland Park, Ill., assignor to
Burgess-Day, Inc., Libertyville, Ill., a corporation of
Delaware

Filed Mar. 17, 1966, Ser. No. 1,523

Term of patent 14 years

(Cl. D13—1)

FIG. 1 is a front perspective view of a telephone booth structure or the like embodying my new design, the seats being shown in normal, unoccupied position; FIG. 2 is a top plan view, and

FIG. 3 is a side view showing the seats in the position when occupied.

The essential features of my design reside in the portions shown in full lines.

I claim:

The ornamental design for a telephone booth structure or the like, substantially as shown and described.
